UNITED STATES PATENT OFFICE.

CHARLES B. MILLER, OF PHILADELPHIA, PENNSYLVANIA.

DESIGN FOR A BOTTLE.

SPECIFICATION forming part of Design No. 19,108, dated May 21, 1889.

Application filed April 19, 1889. Serial No. 307,854. Term of patent 3½ years.

To all whom it may concern:

Be it known that I, CHARLES B. MILLER, a citizen of the United States, residing at Philadelphia, in the county of Philadelphia and State of Pennsylvania, have invented a certain new and useful Design for Bottles; and I do declare the following to be a full, clear, and exact description of the invention, such as will enable others skilled in the art to 10 which it appertains to make and use the same, reference being had to the accompanying drawing, and to the letters and figures of reference marked thereon, which form a part of this specification.

15 In the drawing I have shown a perspective view of a bottle constructed in accordance with my design.

The general contour of the bottle is such as 20 to represent a light-house, showing the form of the building, together with its door, windows, and outside gallery near the top of the building.

By reference to the accompanying drawing it will be seen that the bottle is round in 25 cross-section, is provided with a broad and substantial base, and from the base to the top of the bottle the diameter is gradually lessened. At the base of the bottle the foundation-wall of the light-house is represented, and a door 30 is shown as representing the door or entrance

to the building. Above the doorway the face of the bottle is designed to represent the body of the building, the walls of which are shown as constructed of brick or stone. At intervals windows are shown, and at a point near 35 the upper end of the bottle an outside gallery is shown with a doorway opening upon the said gallery. A short distance above the gallery the wall of the building is shown as terminating, the top of the wall being provided with a slightly-projecting cornice, which is indicated by the annular rings or raised portion *a*. Directly above the cornice *a* are represented the windows *A* of the light-house, while the space above the said windows and 45 adjacent to the upper end of the bottle is provided with a series of corrugations constituting the cap or cover.

What I claim is—

The design for a bottle herein shown and 50 described, the same having the general appearance of a light-house provided with a corrugated cap or cover, as set forth.

In testimony whereof I affix my signature in presence of two witnesses.

CHARLES B. MILLER.
